United States Patent Office.

MICHAEL RITCHIEY, OF PATERSON, NEW JERSEY.

Letters Patent No. 101,767, dated April 12, 1870.

IMPROVEMENT IN STEAM-GENERATORS.

The Schedule referred to in these Letters Patent and making part of the same.

To all whom it may concern:

Be it known that I, MICHAEL RITCHIEY, of Paterson, in the county of Passaic and State of New Jersey, have invented a new and improved Steam-Generator; and I do hereby declare that the following is a full, clear, and exact description thereof, which will enable others skilled in the art to make and use the same, reference being had to the accompanying drawings forming part of this specification, in which—

Figure 1 represents an end view of my improved steam-generator.

Figure 2 is a side view, partly in section, of the same.

Similar letters of reference indicate corresponding parts.

This invention relates to a new steam-generator, which is so constructed that the water before it enters the main boiler will be thoroughly heated, and that, when the pumping ceases, a complete circulation will be kept up in the same.

The sides of the fire-box are formed by hollow water-boxes A A', made of iron, and set up vertical, as shown in fig. 1, the main boiler B being arranged between them.

The boiler is of suitable construction.

On the inner edges of the boxes A A' are arranged zigzag pipes C C' respectively, the upper parts of the two pipes being, under the boiler, connected with each other by a transverse pipe D.

The feed-water first enters the lower end of the pipe C, where a cock, a, is opened for its reception.

It passes then through the pipes C, D, and C', and is heated therein preparatory to entering the box A'.

From the lower end of the pipe C' the water flows into the lower part of the box A', and is therein further heated.

Through a short pipe, b, it flows from the top of A' into the boiler B.

From the boiler the colder water flows down through a pipe, d, into the box A, and the most heated contents of the latter flow through another pipe, e, from the top of the box A back into the boiler. Thus, the water is frequently passed around the fire-box to absorb as much heat as possible.

A pipe, E, extends from the boiler to the lower end of the pipe C.

While water is pumped into the apparatus the cock f in the pipe E is closed.

When pumping, however, ceases, the cock a is closed and b opened, and then a complete circuit is provided to enable the water to return to the lower

end of C, and to pass up again in the same, and thus circulate through the entire apparatus.

By connecting the lower end of the pipe C with the boiler B, the boxes A' A may be omitted and the pipes C' C D E used, and, by omitting the pipes C' C D, the boxes A' A may be used, but the best results are obtained when both pipes and boxes are used together.

It will be observed that the primary objects of this invention are two, namely, to provide the boiler with hot water in the first place, and subsequently to utilize the heat product of the fire-box.

The first I accomplish by causing the water, as it is pumped in, to pass through a series of heated pipes and then into a hot chamber before it finds its way into the boiler. It is pumped into pipe C, through which and the pipes D C' it passes into chamber A', from whence it is conducted in a heated state into the boiler through the induction-pipe b.

At the time of its entrance into the boiler it is hot, but has not attained a temperature to generate steam.

After the requisite supply has been pumped in, the next object is to convert it into steam with the minimum expenditure of heat.

By allowing the water to circulate not only against the heating-surface of the boiler but also through the pipes and water-chambers, all under the direct and immediate influence of the fire, almost the entire heat force is economized.

As the water in these pipes or chambers attains a temperature exceeding that in the boiler, it at once rises through the intermediate pipes to the boiler, and to the surface of the water therein.

In other words, the more highly heated and expanded particles will always rise to the top of the boiler, exactly in the same manner and on the same principle as if the pipes, chambers, and boiler were all one vessel.

The cooler stratum of water always being lowest, that in the boiler will sink through the pipe d and through the chamber A until it reaches the bottom thereof, or water, of its own or less temperature.

On the other hand, as that in A becomes highly heated by its close proximity to the fire, it will rise up through that chamber and pass into the boiler through the induction-pipe e.

The auxiliary pipe E is employed as an induction-pipe to connect the boiler with pipes C D C', so that cooler portions of the water may find their way to the heating-chamber A'. From this, when sufficiently heated, it passes through induction-pipe b to the boiler.

Having thus described my invention,
I claim as new and desire to secure by Letters
Patent—

1. Supplying hot-water to a steam-generator by means of a heating-chamber, A', and series of winding pipes all placed contiguous to the fire, whereby the water is retarded in its progress and heated before it reaches the boiler, as set forth.
2. The combination with boiler of inlets and out-

lets b d e, chambers A A', and pipes C C' D E, all arranged with respect to the furnace in the manner described.

The above specification of my invention signed by me this 3d day of August, 1869.

MICHAEL RITCHHEY.
